(57) **CLAIM**

The ornamental design for a portion of a display screen with an icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a portion of a display screen with an icon showing our new design;

FIG. 2 is a front view of a second embodiment thereof; and, FIG. 3 is a front view of a third embodiment thereof.

The dot-dash broken lines in the drawings illustrate a portion of the display screen and form no part of the claimed design.

1 Claim, 3 Drawing Sheets
(1 of 3 Drawing Sheet(s) Filed in Color)
